LOCKING MECHANISM

Application filed December 28, 1928. Serial No. 328,987.

This invention relates broadly to certain new and useful improvements in locking mechanism, but more particularly to a registering device for locks, and while primarily intended for baggage or luggage locks, it will be obvious that registering device may be embodied in any type of locks wherein it is found to be applicable.

The primary object of the invention is to provide a register for locks, which will visibly display a different designation each time that the lock is released from the locking position; under such conditions the lawful owner can at once see that the lock mechanism has been operated by an unauthorized person, and the latter will be deterred from tampering with registering locking mechanism as knowledge of such tampering will be apparent to the owner at once.

Further objects of the invention are to provide a device of the class stated which is simple in its construction and arrangement, durable and efficient in its use, compact, positive in its action, attractive in appearance and comparatively inexpensive to manufacture.

With the foregoing and other objects in view which will appear as the description proceeds, the invention resides in the combination and arrangement of parts and in the details of construction hereinafter described and claimed, it being understood that changes in the precise embodiment of the invention hereinafter disclosed can be made within the scope of what is claimed without departing from the spirit of the invention.

In the drawing wherein like numerals of reference designate corresponding parts throughout the several views:—

Figure 1 is a top plan view of a luggage trunk lock in the securing position and embodying the invention.

Figure 2 is a similar view thereof in the releasing position.

Figure 3 is a top plan view of the locking plate casing.

Figure 4 is a side view thereof, partly in cross section.

Referring in detail to the drawing 1 denotes a hasp member which is hingedly connected at its rear end, as at 2, to a hinge plate 3. The hasp member 1 is associated with a locking plate 4 and carries a depending latch casing 5 which encloses the latching elements 6. The latch casing 5 is preferably cylindrical in contour and is adapted to extend through an opening 7 formed in the locking plate 4, and into the pocket 8 formed by the locking plate casing 9. The latter is fixed to the under side of the locking plate 4 and includes a forwardly disposed casing extension 10 for the purpose to be described.

The engagement of the latching elements 6 with the under side of the edge margins 65 of the wall of the locking plate opening 7, secures the hasp member 1 in the securing position, and necessitates the use of the key to effect its release.

The locking mechanism herein illustrated and above described is identical to locking mechanisms now commonly used for trunks, and its construction and operation is well known in the art to which the invention appertains, and is not thought to require a more detailed description.

The feature of the present invention resides in the combination of a register with a locking mechanism that will visibly display a different designation each time that the locking mechanism is released from the locking position.

A register 11 is suitably mounted for operation in the casing extension 10, to position the same directly beneath an opening 12 formed in the forward end of the locking plate 4. Only the recording row of numerical indicia 13, will, at all times be visible through the register opening 12. The register 11 may comprise any suitable contrivance

of the type now commonly employed for noting the performance of various devices.

The construction and operation of this type of register is well known, and no claim is made to the structure thereof as part of this invention. We claim, however, the co-operation with and combination of this type of register, the specific arrangement and disposition of which provides a most efficient medium for deterring unauthorized persons from tampering with locking mechanisms embodying the same.

The register 11 is operatively connected to an actuating lever 14, which is pivotally mounted on a supporting bolt 15 fixed in a side wall of the casing extension 10. The free end of the actuating lever 14 projects into the pocket 8 and inclines upwardly to position the same in the path of travel of the latch casing 5. A spiral spring 16, having one end fixed to the locking plate casing 9 and the other end thereof to the actuating lever 14, is mounted on the supporting bolt 15 and functions to return the actuating lever 14 to its normal position.

In practice, the operation of the present invention is as follows: In locking the mechanism the hasp member 1 is swung over the locking plate 4 and the latch casing 5 is forced into the pocket 8 until the latching elements 6 engage the under side edge margins of the wall of the locking plate opening 7. The mechanism is now in the locked position. While the latch casing 5 is being forced into the pocket 8, as above stated, the bottom thereof will engage and depress the actuating lever 14 and maintain the latter in such depressed position as long as the mechanism remains locked.

When the latching elements 5 are released by the key or otherwise and the hasp member 1 shifted outwardly to withdraw the latch casing 5 from the pocket 8, the action of the spring 16 will return the depressed actuating lever 14 to its normal position. Such return movement of the actuating lever 14 will effect the operation of the register 11 to properly record same.

In the use of our improved locking mechanism it is, of course, essential that the lawful owner of the same acquaint himself and retain a record of the indicia 13, showing on the register 11 when the mechanism is locked, so he will distinguish at a glance whether the mechanism has been released or not.

We are well aware of the fact that the present invention does not render unauthorized release of the locking mechanism impossible, but it does provide a deterrent owing to its detection on sight.

What we claim is:

The combination with a lock including a shiftable hasp member carrying a latch casing and a fixed locking plate formed with a pocket casing adapted for the reception of

said latch casing, of a counter register fixed to said locking plate, a spring controlled actuating lever operatively connecting with said counter register and having its free end projecting into said pocket casing whereby the movement of said latch casing into and from said pocket casing will shift said actuating lever to operate said counter register.

In testimony whereof we affix our signatures.

MAX J. SCHWIMER.
JOHN A. REPCHECK.
